UNITED STATES PATENT OFFICE.

CHARLES A. BARNARD, OF GARDNER, MASSACHUSETTS.

WOOD-BENDING MACHINE.

1,249,302.

Specification of Letters Patent. Patented Dec. 11, 1917.

Application filed August 9, 1917. Serial No. 185,282.

To all whom it may concern:

Be it known that I, CHARLES A. BARNARD, a citizen of the United States, residing at Gardner, in the county of Worcester and State of Massachusetts, have invented a new and useful Wood-Bending Machine, of which the following is a specification.

This invention relates to a wood bending machine, and particularly to certain improvements in the removable clamping devices in which the stock remains during the drying process.

In the operation of bending relatively thick or heavy pieces of wood, such for instance as are used in the manufacture of seat frames, steering wheel rims and similar objects, it is the modern practice to place steamed stock in a bending machine and to secure one or both ends of the stock to bending heads mounted for both angular and longitudinal movement. By such movement the stock is brought into the desired form, commonly circular, in which position it is secured before removal from the machine.

It is the general object of my invention to improve the construction of the bending heads and of the clamping devices removably mounted thereon, said devices being adapted to retain the bent stock in shape after it is removed from the machine for drying.

With this general object in view an important feature of my invention relates to novel elements of construction in the bending heads and more particularly to the provision therein of radially adjustable flanges which may be readily withdrawn or collapsed to permit easy removal of the bent stock therefrom.

A further feature of my invention relates to the construction of the clamping blocks, each having a flange portion corresponding to the adjustable flange on the bending head but comprising a relatively small portion of a complete circumference. I have also made important improvements in the construction of the flexible metal band or strap which cooperates with the clamping blocks to hold the stock in shape during the drying operation.

My invention further relates to certain arrangements and combinations of parts hereinafter described and more particularly pointed out in the appended claims.

A preferred form of my invention is 55 shown in the drawings, in which—

Figure 1 is a plan view of a bending machine embodying my improvements;

Fig. 2 is a front elevation of the machine shown in Fig. 1;

Fig. 3 is a sectional transverse elevation taken along the line 3—3 in Fig. 2;

Fig. 4 is a partial longitudinal sectional elevation taken along the line 4—4 in Fig. 1;

Fig. 5 is a partial plan view showing the 65 bending heads in final position;

Fig. 6 is a plan view of the clamping blocks and flexible strap as they appear when removed with the stock from the machine;

Fig. 7 is a front elevation of the parts 70 shown in Fig. 6;

Fig. 8 is a plan view of a right-hand clamping block, showing the end of the stock and the flexible band in position therein;

Fig. 9 is a plan view of a left-hand clamp- 75 ing block, and

Fig. 10 is a perspective view of one end of the flexible strap.

Referring first to Figs. 1, 2 and 3 I have shown my improvements embodied in a bending machine of a common type comprising a frame 20 and a driving gear 21 mounted upon a vertical shaft 22 supported in bearings (not shown) in said frame, said gear being alternately rotated in opposite directions by any suitable driving mechanism. The gear 21 engages racks 23—24 longitudinally slidable in the frame 20 and connected respectively by studs 23^a and 24^a to plates 25 and 26 also slidable in suitable longitudinal guideways in the frame 20. The parts are so disposed that alternate rotation of the gear 21 will move the plates 25—26 alternately toward and away from each other.

A bending head 30 is rotatable about a 95 stud 31 (Fig. 4) fixed in the plate 25, said head supporting a segment gear 32 and a semi-circular plate 33. The segment gear 32 extends over something more than a semi-circumference and at one end the gear is 100 cut away at one side to provide a series of teeth 32^a (Fig. 3) of one-half the length of the teeth in the main portion of the gear. The purpose of this construction will be hereinafter described.

A flanged member 34 is secured to the semi-circular plate 33 by a bolt and slot connection which permits radial movement

of said flanged member. Upon its outer or circumferential portion said member is provided with a vertical flange 35 shown in the drawings as covering approximately 120 degrees or one-third of a complete circle. A cam 36 is mounted upon a stud 37 secured in the plate 33 and comprises means for moving the flanged member 34 to its outer or operative position. The cam 36 is manually adjustable by a handle 38.

The machine shown in the drawings is of the double-head type and the construction of the second or left hand head 40 shown in Fig. 1 is substantially identical with the construction of the head 30 previously described. The left-hand head 40 is rotatable on a stud 41 in the plate 26 and supports a gear 42 and flange 45, said member being movable outwardly by a cam 46 mounted on a stud 47 and controlled by a handle 48. The segment gears 32 and 42 are both engaged by a rack 49 fixed in the frame 20.

The plates 33 and 43 have fixed therein studs 50 and 51 upon which are placed clamping blocks 52 and 53. The studs 50 and 51 are of different heights, as shown in dotted lines in Fig. 2 and the blocks 52 and 53 are of right and left hand construction, as best shown in Figs. 8 and 9. Each block comprises a flanged portion 54 and an outwardly extending hook-shaped portion 55 having a recess or pocket 56 therein adapted to receive one end of a flexible metal band 60 to be described. Each clamping block is also provided with an inwardly extending straight portion 57, said portions 57 being offset so that they are adjacent and over-lapping in their final position as shown in Figs. 5 and 6. The blocks are so designed that they will receive a piece of stock S lying at an angle to the plane of the frame 20 as indicated in Fig. 2. This disposition of the stock permits one end of the stock to be bent above the other so that the parts overlap vertically at the end of the bending operation, as shown in Fig. 7.

A clamp 58 is provided for each pair of blocks 52 and 53, said clamp being placed over the projections 57 when the parts reach their final position and thus holding the blocks securely together after they are removed from the machine.

The straps 60 each comprise a single strip of sheet metal having the ends reversely bent to U-shape and having blocks 61 positioned between the sides of each U-shaped bend and rigidly secured to the outer or reversed portion of the loop. I have found that it is a matter of considerable importance to secure the block 61 to the strap 60 upon one side only of the reverse bend. As thus made, the strap more readily adjusts itself to different positions and the expense of manufacture is also decreased.

65 The stock S rests on an inclined bracket

65 (Fig. 3) secured to the frame 20 at the back of the machine and a clamping jaw 66 is provided for securely holding the stock S in position. The jaw 66 is slideable forwardly upon the top of the bracket 65 and 70 its rear or outer end is connected by links 67 to studs 68 in said bracket. As the jaw moves forward the links 67 raise the rear edge of the jaw, thus causing the jaw to bear upon the front edge portion only of the 75 stock S, an arrangement which has been found extremely desirable in a bending machine of this type. Hand wheels 69 are provided for clamping the jaw 66 upon the stock.

Having described the details of construction of my invention, I will now describe the operation thereof.

A piece of stock S is first placed on the bracket 65, backed up by one of the flexible 85 bands or straps 60. The ends of the stock extend within the hook-shaped portions 55 of the clamping blocks 52 and 53 and the ends of the strap 60 are received within the pockets 56 in said portions. The adjustable 90 flanged members 34 and 44 have previously been moved outwardly to operative position by means of the cams 36 and 46.

As the gear 21 is revolved in the direction of the arrow A, Fig. 1, the racks 23 and 24 move the plates 25 and 26 and the bending heads 30 and 40 toward each other until they reach the position shown in Fig. 5. As the heads move toward each other, the segment gears 32 and 42 are rotated by their engagement with the rack 49 at the rear of the machine and the bending heads are thus given angular movement. The parts are so proportioned that this angular movement bends the stock smoothly about the flanges 105 54 on the clamping blocks 51 and 52 and the flanges 35 and 45 on the flanged members 34 and 44. This movement continues until the semi-circular plates 33 and 43 are positioned adjacent each other as shown in Fig. 110 5, such approach of the plates being permitted by the half-length construction of certain teeth 32^a and 42^a of the segment gears 32 and 42, which construction permits the leading end of each gear to overlap the 115 corresponding portion of the other gear.

After the parts have reached the position shown in Fig. 5, a clamp 58 is placed over the end of the projecting portions 57 of the blocks 51 and 52 and the flanged members 120 34 and 44 are then withdrawn, permitting easy removal of the clamping blocks 51 and 52 and the flexible strip 60 together with the stock S. These parts are then placed in a drying chamber until the stock has been 125 thoroughly dried in its bent position.

Reference to Fig. 6 will show that the clamping blocks 52 and 53 engage the stock S upon a small portion only of the inner surface, thereby permitting access of the 130

dry air to this surface of the stock and greatly facilitating the drying operation. Such access may be further facilitated by slightly shortening the radius of the flanges 5 54 in their end portions, as indicated at 54^a in Fig. 8.

It is customary to provide several hundred pairs of clamping blocks 51 and 52 and a corresponding number of straps 60 so that 10 the operation of the machine may continue while the parts removed with the stock are in the drying chamber.

Having thus described my invention it will be evident that changes and modifications can be made therein by those skilled in the art without departing from the spirit and scope thereof as set forth in the claims and I do not wish to be otherwise limited to the details herein disclosed, but what I 15 claim is:—

1. A wood bending machine having in combination a pair of rotatable heads, each head having a bending flange thereon extending around approximately one-third of 25 a circumference, a clamping block for each head having a flanged portion coöperating with said flange on the head, and means to secure said blocks together, said means permitting their removal as a unit from said 30 machine.

2. A bending machine having in combination a pair of rotatable bending heads, flanges thereon each extending over approximately one third of a circumference and a 35 pair of clamping blocks detachably mounted on said heads, and having flanges coöperating with the flanges on said heads and completing the surface desired for shaping the stock.

40 3. A wood bending machine having in combination a pair of bending heads, each having a flange thereon extending around approximately one-third of a circumference, said flanges being radially movable, means 45 to hold said flanges in operative position, a clamping block for each head having a flanged portion coöperating with the flange on the head, and means to secure said blocks together.

50 4. A wood bending machine having in combination semi-circular rotatable bending heads, flanged plates mounted for radial movement thereon, manually operable cams to force said plates outwardly to operative 55 position, clamping blocks having coöperating flanged portions, and means to secure said blocks to each other, said blocks being thereafter removable from the machine as a unit with the stock.

60 5. In a wood bending machine, the combination of a pair of bending heads each

having a stud eccentrically mounted thereon, clamping blocks detachably mounted on said studs, and means to secure said blocks together after the bending operation, said 65 blocks being thereafter removable from said heads as a unit.

6. In a wood bending machine, the combination of a pair of bending heads each having a stud eccentrically mounted thereon, 70 clamping blocks detachably mounted on said studs, said studs being of different lengths and supporting said blocks at different elevations, and means to secure said blocks together after the bending operation, 75 said blocks being thereafter removable from said heads as a unit.

7. In a wood bending machine, the combination of a pair of bending heads, clamping blocks detachably mounted thereon, said 80 blocks being flanged and having offset overlapping portions, and means to clamp said portions together, thereby forming a structure removable as a unit from said heads.

8. A bending machine having in combination a pair of clamping blocks, each having a limited flanged surface, means to give said blocks a combined angular and longitudinal movement, a flexible metallic strap secured to said blocks outside of the 90 stock to be bent, and means to clamp said blocks together after the bending operation, said blocks and strap being thereafter removable as a unit, together with the stock secured in bent position thereby. 95

9. In a wood bending machine, the combination of semi-circular rotatable bending heads, segment gears thereon having extended portions of reduced thickness overlapping in certain positions of said heads, 100 flanges on said heads extending partially around the curved periphery of each head, a clamping block for each head having a flanged portion completing the curved periphery of its head, and means to secure 105 said blocks together.

10. A wood bending machine having, in combination, a pair of rotatable heads, each head having a segmental flange portion, a pair of detachable clamping blocks mounted 110 to move angularly and longitudinally with said heads, said blocks also each having a segmental flange portion, the combined length of the segmental flange portions of said heads and blocks being at least sufficient to substantially equal a complete circumference, and means to secure said blocks together, said means permitting the removal of said blocks as a unit from said machine.

In testimony whereof I have hereunto 115 affixed my signature.

CHARLES A. BARNARD.
